HANDLE FOR A DISHWASHER DOOR OR THE LIKE

Samuel K. Wald, Salem, Ohio, assignor, by mesne assignments, to American Radiator & Standard Sanitary Corporation, New York, N. Y., a corporation of Delaware

Application December 29, 1955, Serial No. 39,514

Term of patent 14 years

(Cl. D49—1)

FIG. 1

FIG. 3

Fig. 1 is a front elevation view of a handle for a dishwasher door or the like, showing my new design.

Fig. 2 is a side elevation view of the design shown in Fig. 1.

Fig. 3 is a section taken at line 3—3 of Fig. 1.

The dominant features of the design reside in the portions shown in full lines.

I claim:

The ornamental design for a handle for a dishwasher door or the like, substantially as shown and described.
